United States Patent Office.

JAMES A. COLE, OF ADAMS, NEW YORK.

Letters Patent No. 93,059, dated July 27, 1869.

IMPROVED CAR-BRAKE AND STARTER.

The Schedule referred to in these Letters Patent and making part of the same.

To all whom it may concern:

Be it known that I, JAMES A. COLE, of Adams, in the county of Jefferson, and State of New York, have invented a new and useful Improvement in Devices for Stopping and Starting Street-Cars; and I do hereby declare the following to be a full, clear, and exact description of the same, reference being had to the accompanying drawings, which are made part of this specification.

I employ one or more springs, of suitable form and material, attached to a separate shaft beneath the car, connected to one or both axles by suitable gearing, and operating in one condition of the gearing, by being wound up on its shaft, to stop the car; and, on the gearing being shifted, by its resiliency to start or assist in starting it, its shaft, on the completion of its action in starting the car, being automatically thrown out of gear with the axle or axles, so as to prevent its being strained.

My invention consists in a novel combination of parts for facilitating the connection and disconnection of the spring-shaft and axle, as required, and in a provision, of novel construction, for automatically throwing the device out of gear.

In the drawings—

Figure 1 represents a plan view of the bed-frame and running-gear of a car provided with my improved stopping and starting-mechanism, the latter being shown applied to one axle only, and provision made for its application to the other, when desired.

Figure 2 is a vertical longitudinal section of the same, on the line $x-x$, fig. 1.

Figures 3 and 4 are vertical transverse sections of the same, on the lines $y-y$ and $z-z$, fig. 1.

A represents the bed-frame of the car,

B B' the axles, and

C the wheels.

D represents a metallic shaft, supported in suitable bearings in the frame A, and preferably arranged longitudinally of the car, at a central point between the wheels, and in a horizontal position, as shown.

The shaft D is provided, on its end adjoining the axle to which the provision is to be applied, with a mitre gear-wheel, E, keyed thereon, and meshing alternately, in the double operation of the device, with corresponding gears F F', on the axle B. These gears F F' are connected to the axle by means of splines, so as to allow of their sliding longitudinally on the axle, but cause them to rotate in unison therewith.

They are pressed apart by a spring, G, coiled around the axle, or applied in other suitable form between them, and their distension is limited by means of stops b on the axle, as shown, or on the frame.

In their distended position, the gears F and F' are both out of mesh with E. To enable them to be thrown into gear as desired, the gears F F' are con-

structed with hubs f f', for the reception of forks H H', which may be pivoted to levers I I', by which to operate them, and supported on a plate, or bar, J, spanning the frame A over the axle, and guided in a path in line with the axis of the axle, by slots j j', as shown.

The levers I I' are pivoted, at i i', to the frame, and engage with the forks H H' at intermediate points, and may have the power applied to them, directly or through suitable connection, at their outer end, to shift the gears. The movement of either of the levers I I' toward the middle of the cars, brings the gears F or F' into mesh with E.

K represents a strong spiral or helical spring, of steel or other suitable material, attached at one end to the frame A, and at the other to the shaft D, as represented most clearly in fig. 4.

With the arrangement shown, the gear F being in mesh with the gear E on said shaft D, as represented, and the car being drawn in the direction indicated by the arrow, the continued motion of the car will tend to wind up said spring on the shaft, the increased power required to do this retarding and finally stopping the movement of the car. The lever I' being then pressed toward the centre, so as to bring the gear F' into mesh with E, and the lever I released, the spring G, by the increased pressure it is made to exert by its compression, will throw F out of gear, and the accumulated force of the spring K will then be exerted to start the car in the direction it was originally pursuing, the relative directions at which the axle and the spring-shaft rotate being reversed by said shifting of the gearing. Were the parts allowed to remain in this position, the continued forward movement of the car, after the spring has fully uncoiled, would cause it to again stop the car, by its being wound on its shaft in an opposite direction from that first described, which motion would, besides, impair, and perhaps break the spring.

To prevent this, and to automatically throw the gears out of mesh at the proper moment, a supplementary lever is employed, fulcrumed at l, and connected with the lever I' to its fork H', by which the gear F' (the one in gear in starting) is engaged. Said lever L is extended to within a suitable distance of the shaft D, and is there provided with an oblique or inclined bearing-face, l', for the engagement of an inclined or cam surface, m, of a traversing-nut, M, the engagement of which with said lever through the described connection throws said gear F' out of mesh with E, and thus severs the connection between the spring-shaft and axle.

The nut M is held in the proper position to engage with the lever L by means of a stud, or projection, m', traversing a longitudinal slot, n, in a plate, N, attached to the frame in convenient position. It is act-

uated by means of a screw-thread, *d*, formed on the shaft *D*, as represented in fig. 2, and so arranged as to advance said nut in the motion of unwinding the spring, and to retract it in winding up the spring.

The device may be applied in the same manner to both axles, if desired. This would be the preferable mode, the devices being so arranged as that one set (the front) should operate in the manner described in each direction.

With the single device, as shown, the car would have to be turned in running back, so as to cause its axles to run always in the one direction. A single device could, however, be adapted to operate, as described, in both directions, by the addition of suitable gearing.

When the device is applied to both axles, one spring and spring-shaft may serve for both, as indicated in figs. 1 and 2, or two spring-shafts may be employed, if preferred, and in either case two or more springs may be employed.

When desired, the mechanism, instead of being mounted in a frame, as described, may be attached directly to the under side of the car-body, the shafts being supported in suitable hangers.

Having thus described my invention, the following is what I claim as new therein, and desire to secure by Letters Patent:

1. The combination, substantially as described, with the axle *B* and spring-shaft *D E* of the gears *F F'*, sliding on said axle *D*, the distending-spring *G*, forks *H H'*, and levers *I I'*, all arranged to operate in the manner described, for the purpose specified.

2. The supplementary lever *L*, operated automatically by the spring-shaft, substantially in the manner described, in combination with said spring-shaft *D E*, the gear *F'*, and axle *B*, substantially as and for the purpose set forth.

3. The traversing-nut *M*, operated by means of the screw *d* on the spring-shaft *D E*, and provided with the cam-surface *m*, in combination with the lever *L*, gear *F'*, and shaft *B*, substantially as and for the purpose described.

JAMES A. COLE.
